UNITED STATES PATENT OFFICE.

EARL V. GILBERT AND GEORGE H. KRAMER, OF DAYTON, OHIO, ASSIGNORS TO THE KRAMER BROTHERS FOUNDRY COMPANY, OF DAYTON, OHIO, A CORPORATION OF OHIO.

DUMPING-GRAVE.

1,205,616.

Specification of Letters Patent. Patented Nov. 21, 1916.

Application filed December 8, 1914. Serial No. 876,160.

To all whom it may concern:

Be it known that we, EARL V. GILBERT and GEORGE H. KRAMER, both citizens of the United States, residing at Dayton, in the county of Montgomery and State of Ohio, have invented certain new and useful Improvements in Dumping-Grates, of which the following is a specification.

Our invention relates to grates for boilers, furnaces or similar purposes and particularly to a shaking or dumping grate and to the operating means therefor.

The object of the invention is to simplify the structure as well as the means and mode of operation of such devices whereby they will not only be cheapened in construction but will be more efficient in use, easily operated, and unlikely to get out of repair.

A further object of the invention is to provide an improved form of grate unit in which the fire will be supported above the truss bars or frame of the unit thereby reducing to minimum the tendency to warp the frame or support for the grids under the influence of intense heat.

A further object of the invention is to provide an improved form of mounting for the oscillatory grate unit which, while permitting the ready assembling of the parts, will prevent the accidental disengagement thereof during the shaking or dumping operation.

Further object of the invention is to provide improved means for oscillating the grate units in unison and for normally limiting such oscillation to a comparatively small degree of movement but permitting the degree of oscillation to be increased at will.

With the above primary and other incidental objects in view, as will more fully appear in the specification, the invention consists of the features of construction, the parts and combinations thereof, and the mode of operation, or their equivalents, as hereinafter described and set forth in the claims.

Referring to the drawings, Figure 1 is a perspective view of a grate setting showing one section in its normal position while the second section is in dumping position. Fig.

2 is a longitudinal sectional view through one of the grate sections showing the grate units at the limit of their shaking movement. Fig. 3 is a detail perspective view of one of the oscillatory grate units viewed from its under side. Fig. 4 is a detail view of the trunnion connection or mounting of the grate units. Fig. 5 is a detail view of the locking detent.

Like parts are indicated by similar characters of reference throughout the several views.

Referring to the drawings, 1—1 are the bearing bars or supporting rails resting at their forward ends on a suitable frame 2 and at their rearward ends supported upon the bridge wall 3. Arranged transversely to the bearing bars 1—1, at their forward and rearward ends, are stationary grate bars 4. Each of these stationary grate bars comprises a main body from which project laterally a plurality of spaced short fingers or lugs 5. These fingers or lugs 5 may project at right angles to the main body of the stationary bar, as shown in Fig. 1, or may be arranged at an inclination thereto agreeing with the inclination of the grids of the oscillatory grate units herein-after described, which variation is so obvious as not to require illustration.

The rails or supporting bars 1 are provided upon their upper edge at suitable intervals with arcuate notches or recesses 6 in which the trunnions of the oscillatory grate units herein-after described are mounted. These openings or recesses 6 are so located in the rails or bearing bars with relation to the top edge of the bar that the opening into the recess is of less width than the diameter of the opening below the edge of the bar. That is, the edge of the bearing bar or rail intersects the opening intermediate the center of the recess and its projected periphery. The trunnion 7 of the oscillatory grate units herein-after mentioned is flattened upon its upper side to correspond with the shape of the notch or recess 6. The dimensions of the trunnion are such that its diameter measured perpendicular to the flat side thereof is equal to the distance between the shoulders of the

notch or recess 6. This permits the trunnion to be inserted into the notch when turned to a position as shown in Fig. 4. After the trunnion is seated in the notch 5 the oscillation of the grate unit to the positions shown in Figs. 1 and 2 will prevent the withdrawal of the trunnion from the recess or notch due to the overhanging shoulders of the notch which conform to the arcuate 10 periphery of the trunnion.

The oscillatory grate units each comprise a main frame 8 substantially rectangular in shape and provided with medially disposed longitudinal and transverse truss bars 9 and 10 inclined from their centers outward whereby said truss bars will be of greater depth at their juncture in the center of the grate unit than at their juncture with the frame 8 at the edges of the unit. There is 15 thus provided an excess of material at the center of the grate where it is subjected to intense heat and less material at the edges of the grate where the heat is less intense. By this means the variation in the intensity 20 of the heat is compensated for by the distribution of the metal in the supporting frame of the grate unit.

Formed integral with the frame 8 and the truss bars 9 and 10 but projecting above the 30 level thereof are a plurality of grids or grate bars arranged in spaced relation or separated one from the other and positioned in inclined or diagonal relation with the frame 8. It is to be noted that the frame extends 35 only to the under side of these grids or grate bars and that the spaces intermediate the bars are open throughout their entire length except at the end of the oscillatory unit where terminal bars 12 are provided with 40 which the adjacent diagonal bars 11 merge. The grids or grate bars 11 and 12 project slightly beyond the limits of the frame 8 and are preferably slightly beveled or prism shaped whereby their upper faces are 45 slightly wider than their lower faces.

The location of the grids or bars 11 above the level of the frame 8 and their spaced relation one from the other permits a free and uninterrupted circulation of air intermediate the bars. This air space is slightly increased by the inclined or wedge shape of the bars. The grids of succeeding units are arranged to register one with the other, as 50 shown clearly in Fig. 1, and the grids or bars of the terminal grate units register with the studs or fingers 5 of the stationary bars 4. This construction provides continuous air spaces throughout the entire length of the grate. The circulation of air 55 intermediate the grate bars is not interrupted by the projection of the frame 8 nor by unregistered ends of the bars or grids of the succeeding units.

The terminal bars or grids 12 are located

in spaced relation with the rails or supporting bars 1 from which they are separated by interposed shoulders 13 adjacent to the trunnions 7.

Projecting from the under side of the frame 8 and preferably formed integral therewith is a rock arm 14 by which the grate unit is oscillated. A reciprocatory bar 15 is pivotally engaged with the rock arm 14 of each of the grate units of the series. A pitman 16 connects the reciprocatory bar 15, 75 or any one of the rock arms 14 connected to said bar, with an oscillatory operating lever 17 which is pivoted at 18 to a bracket arm 19 projecting from the frame 2. This arm 19 is provided with a recess 20 the sides of 80 which are preferably undercut or beveled inward toward each other. Pivoted to the operating lever 17 is a detent arm 21 having thereon a beveled or divergent lug 22 which engages in the recess 20 in the arm 19. The 85 lug 22 is of less extent than the recess 20 thereby permitting a limited reciprocatory movement of the lug within the recess upon the oscillation of the operating lever 17. The lug 22, by engaging with the sides of 90 the recess 20, limits the oscillatory movement of the lever 17 and thereby limits the degree of oscillation of the grate units, as shown in Fig. 2. In this figure these grate units are shown in shaking position. The 95 overhanging shoulders of the recess 20 prevent the accidental disengagement of the lug from the recess at the limit of its stroke. By the oscillation of the lever 17 throughout the degree of movement limited by the engagement of the lug 22 with the sides of the recess 20, the grate units are oscillated in 100 unison, first in one direction and then in the other, to free the grate from accumulation of ashes, cinders, etc. When it is desired to 105 discharge the contents of the grate unit the detent arm 21 is lifted upward to lift the lug 22 out of the recess 20 thereby permitting the operating lever 17 an additional movement, as shown at the right in Fig. 1, during 110 which movement the lug 22 will ride upon the upper side of the bracket arm 19. This additional movement of the operating lever 17 causes a corresponding oscillatory movement of the grate unit, as shown in Fig. 1, to 115 discharge the contents thereof.

Adjustably mounted upon the pitman 16 is a weight 23, the momentum of which, as the operating lever 17 is oscillated, completes the movement of the lever and the 120 grate unit. The weight 23 serves as a balance weight, the momentum of which accelerates the oscillatory movement of the grate units, causing them to approach the limit of their movement in either direction 125 with considerable force whereby their abrupt arrest, at the limit of their stroke, will effectually jar or disturb the contents of the

grate units to discharge the refuse therefrom. The weight 23 tends to increase the violence or intensity of movement of the grate unit during the shaking operation 5 thereby increasing its efficiency.

Projecting from the top of the weight 23 is a rib or bead 24 adapted to be engaged by an oscillatory detent 25 mounted upon the frame 2 and provided upon its under 10 surface with two parallel beads or ribs 26. When the grate units are in their normal position the rib 24, upon the weight 23, is in position to be engaged intermediate the ribs 26 of the detent, upon the oscillatory 15 movement of the latter, thereby locking the operating lever 17 and the grate units against movement. The rib 24 has been located upon the weight 23 merely for convenience of manufacture and assembling. 20 It is obvious that a projecting stud or pin carried upon the pitman 16 and engaged by the detent 25 may be used in lieu of the construction before described.

From the above description it will be apparent 25 that there is thus provided a device of the character described possessing the particular features of advantage before enumerated as desirable but which is obviously susceptible of modification in its form, 30 proportion, detail construction or arrangement of parts, without departing from the principle involved or sacrificing any of its advantages.

While in order to comply with the statute 35 the invention has been described in language more or less specific as to certain structural features, it is to be understood that the invention is not limited to any specific details but that the means and construction herein 40 described comprise but one mode of putting the invention into effect, and the invention is therefore claimed broadly in any of its possible forms or modifications within the scope of the appended claims.

45 Having thus described our invention, we claim:

1. The combination with an oscillatory grate unit of an operating lever therefor, a detent carried by the lever, fixed stops spaced 50 one from the other and alternately engaged by the detent permitting a limited movement of the lever in either direction of less extent than the full stroke of which said lever is capable, said detent being movable 55 independent of the lever out of position to engage the stops, thereby permitting the lever an additional degree of movement.

2. The combination with an oscillatory grate of an operating lever therefor, an arm 60 pivoted to the lever, a lug on said arm, a rest for the arm having therein a recess having inwardly projecting shoulders beneath which the said lug engages at the

limit of its stroke in either direction, substantially as and for the purpose specified. 65

3. The combination with an oscillatory grate unit of an operating lever therefor, a bracket to which the lever is pivoted said bracket having a recess therein provided with beveled shoulders, an arm 70 pivoted to the operating lever and normally projecting into the recess in the bracket, the engaging portion of the arm being of less extent than the recess, permitting a limited movement of the arm therein, the opposite 75 faces of the engaging portion being beveled to engage beneath the beveled shoulders of the recess adapted by its engagement with the sides of the recess to limit the movement of the lever, said arm being capable 80 of disengagement from the recess by its oscillatory movement about its pivotal connection with the lever to permit the lever an additional movement.

4. The combination with a series of rocking grate bars, of a reciprocating actuating member operatively connected with the several grate bars, a lever connected with said actuating member, two fixed stops arranged in spaced relation one with the other, a detent pivotally mounted on said lever, said detent being movable into and out of position intermediate the said fixed stops, said fixed stops being spaced apart to permit the lever to have limited movement and serving to positively limit the movement of said lever in either direction to a degree less than the full stroke of which said lever is capable, said detent being movable to disengage the same from the stud to permit of 100 a longer movement of said lever.

5. The combination with a series of grate bars, and a reciprocating actuating bar therefor, of a lever connected with said bar, a detent to lock said bar against all 105 movement, a fixed stop, a second detent connected with the lever and co-operating with said stop to permit the said lever to have a limited movement when said first mentioned detent is in its inoperative position, 110 said last detent being also movable into an inoperative position to permit the unlimited movement of said lever.

6. The combination with a rocking grate bar and a device to operate the same comprising a lever, of a detent pivotally mounted upon said lever, two fixed stops arranged to extend on opposite sides of the detent carried by said lever permitting a limited swinging movement of the lever. 115

7. In a grate, the combination with a rocking grate bar, of an operating device therefor including a lever, a detent pivotally mounted on a fixed support and adapted in one position to lock the grate bars against 125 all movement, a fixed stop having a recess

therein, a second detent pivotally mounted on said lever and adapted to project within the recess in the fixed stop, the recess in the fixed stop being proportioned to allow said detent to have movement therein, whereby when the first mentioned detent has been disengaged from the operating device the last mentioned detent will limit the swinging movement of the lever in both directions.

In testimony whereof, we have hereunto set our hands this 30th day of November A. D. 1914.

EARL V. GILBERT.
GEORGE H. KRAMER.
